UNITED STATES PATENT OFFICE.

ALFRED K. MILLER, OF WORCESTER, MASSACHUSETTS, ASSIGNOR OF FIFTY ONE-HUNDREDTHS TO HENRY L. WADSWORTH, OF LEXINGTON, MASSACHUSETTS.

DRYING-MACHINE.

1,080,517.

Specification of Letters Patent.

Patented Dec. 2, 1913.

Application filed November 11, 1911. Serial No. 659,846.

To all whom it may concern:

Be it known that I, ALFRED K. MILLER, of Worcester, in the county of Worcester and State of Massachusetts, have invented 5 certain new and useful Improvements in Drying-Machines, of which the following is a specification.

This invention relates to a device to facilitate the handling and drying of yarn after 10 sizing or other treatment which subsequently requires a yarn drying process.

A drying method frequently employed is to expose a moving horizontal stretch of 15 yarn to an application of heat; the heat application being made in various ways. A drying device based on this principle is desirable as the yarn is easily handled in this position. It is objectionable however because in traveling horizontally the unevenness of tension in the various strands is 20 accentuated and such a drying device necessarily occupies considerable space. Devices for drying by applying heat to the yarn while moving perpendicularly are also used 25 to some extent and overcome the difficulties presented by the drying device acting on a horizontal stretch of yarn. The more serious difficulty presents itself in the second method however of getting the yarn in a succession 30 of windings properly in place to wind through a drying machine or slasher where the yarn passes in a sinuous course over elevated rollers or supports and under depressed rollers or supports. The present 35 methods of carrying the initial ends of the various strands of each new winding under the depressed supports and over the elevated supports all entail much time and labor. The device here presented makes it 40 possible to adjust the yarn preparatory to winding, in a horizontal position so that it is easily handled, through a frame carrying but a short stretch of yarn and occupying but little floor space, and then by elevating 45 some of the supports on which the yarn rests in its initial position, to raise the yarn so it takes a sinuous course, its stretches being nearly perpendicular. Other rollers in the horizontal frame of the machine under 50 which the yarn passes in its initial position and alternating with the elevated rollers, cause the yarn to travel in alternation from the fixed rollers to the elevated rollers thus

exposing to the application of heat extended substantially vertical stretches of yarn while 55 drying the same.

Referring to the plan, Figure 1, is a longitudinal vertical sectional view of a yarn drying machine embodying my invention. Fig. 2, is a horizontal section on line 2—2 of 60 Fig. 1, and a plan view of the part below said line.

My machine as here shown comprises a frame "w" having at one end a sizing device 2 adapted to apply size to the entering yarn 65 y, and at the opposite end a roll or beam 4 on which the sized yarn is wound, the threads or stretches of yarn being guided by a comb 13 and a roll 14 to the beam 4. Journaled in fixed bearings in the frame w are a series 70 of horizontal rolls or yarn guides 1, which are all at the same height and are so arranged that the yarn passes under them and taking a straight course from the sizing device 2 to the guide roll 14. I term these the 75 fixed yarn guides. Journaled in vertical guiding slots or ways 10 in the frame w, are a series of adjustable yarn guides 3 which nominally rest on the lower end of the ways 10 at points below the fixed guides 80 1, the relative arrangement of the guides 1 and 3 being such that the strands y are adapted to be passed between the guides as indicated by full lines in Fig. 1, when the machine is being prepared for use. To the 85 side members of the frame w are attached two flexible cables 6, each cable being attached at one end as indicated at 6^a, Fig. 1. The opposite end of each cable 6, is attached to the periphery of a pulley 7 90 adapted to be rotated to wind up a portion of the cable upon its periphery, the pulley 7 being attached to a shaft 7^a provided with a pulley 5 adapted to be engaged by a driving belt. The cables 6 pass over a series of 95 elevated pulleys 8, mounted on rods or shafts supported by the upper portion of the frame, and under pulley 9 mounted on the adjustable guides 3. When the cables 6 are let out to the maximum extent they hang in elongated loops or bights from the pulley 8 as shown by full lines in Fig. 1, so that the 100 yarn strands y are unaffected by the adjustable guides 3. When the cables 6 are partially taken up by the rotation of the pulley 105 7 the said bights are shortened and the ad-

justable guides 3 are raised and pushed upwardly against the strands y , carrying portions of said strands upwardly in the form of elongated loops or bights as shown by 5 dotted lines in Fig. 1. The strands are thus caused to take sinuous course through the machine when the beam 4 is rotated to wind up the strands and portions of the strands being dispersed in an elongated substantially 10 vertical stretch, arranged in close proximity to each other and adapted to be acted on by ascending currents of heated air. The shaft 7^a is provided with brake drums 12 which are engaged by brake shoes 15 which are 15 preferably bands or straps attached at 16 to the frame and provided with weights 17. The drums and weighted shoes are adapted to sustain the adjustable guides 3 in their elevated positions and permit the said guides 20 to be lowered gradually to their initial position.

While I have shown a plurality of adjustable guides 3, it is obvious that my invention may be embodied in a machine having 25 but one of these guides movable between two fixed guides.

The word thread or threads as used in the claims hereinafter set forth is intended to include woolen, worsted, cotton or other 30 yarn.

Having thus described my invention what I claim as new is,

1. A drying machine comprising a plurality of fixed thread guides, an adjustable 35 thread guide moving from a position on one side of the fixed guides to a position on the other side, means for engaging and moving the leading ends of threads interposed between the fixed guides and the adjustable 40 guide and means for thus moving the adjustable guide, to cause the said threads to take a sinuous course.

2. A drying machine comprising a plurality of fixed thread guides, an adjustable 45 thread guide, movable vertically from a position below to a position above the fixed guides, means for engaging and moving the leading ends of threads interposed between the fixed guides and the adjustable guide, 50 and means for elevating the adjustable guide, to cause the said threads to take a sinuous course.

3. A drying machine comprising a plurality of fixed yarn guides, an adjustable 55 yarn guide, movable vertically from a position below to a position above the fixed guides, a rotary roll arranged to engage and move the leading ends of threads interposed between the fixed guides and the adjustable 60 guide and means for elevating the adjustable guide to cause the said threads to take a sinuous course through the machine.

4. A drying machine comprising a plu-

rality of fixed thread guides, an adjustable 65 thread guide, movable vertically from a position below to a position above the fixed guides, means for engaging and moving the leading ends of threads interposed between the fixed guides and the adjustable guide, 70 means for elevating the adjustable guide, said means including a plurality of flexible cables each attached at one end to a fixed support, elevated pulleys engaged with said cables and supporting the same in bights or 75 loops adapted to support the adjustable guide, and rotary pulleys to which the opposite ends of the cables are attached, said pulleys being adapted to wind up portions 80 of the cables and thus elevate the adjustable guide.

5. A drying machine comprising a frame having side members provided with elongated substantially vertical ways, fixed thread guides located adjacent to and 85 slightly above the lower ends of said ways, an adjustable thread guide movable in said ways from a position below to a position above the fixed guides, means for engaging and moving the leading end of threads interposed between the fixed guides and the adjustable guide, a plurality of flexible cables each attached at one end to a fixed support, elevated pulleys engaged with said cables and supporting the same in bights or 90 loops adapted to support the adjustable guide and rotary pulleys to which the opposite ends of said cables are attached, said pulleys being adapted to wind up portions 95 of the cables and thus elevate the adjustable guide in said ways.

6. A drying machine comprising a plurality of fixed thread guides, an adjustable thread guide, movable vertically from a position below to a position above the fixed 105 guides, means for engaging and moving the leading ends of threads interposed between the fixed guides and the adjustable guide, means for elevating the adjustable guide, said means including a plurality of flexible 110 cables each attached at one end to a fixed support, elevated pulleys engaged with said cables and supporting the same in bights or loops adapted to support the adjustable guide, and rotary pulleys to which the opposite ends of the cables are attached, said 115 pulleys being adapted to wind up portions of the cables and means for holding the pulleys against backward rotation.

7. A drying machine comprising a plurality of fixed thread guides, an adjustable thread guide, movable vertically from a position below to a position above the fixed guides, means for engaging and moving the leading ends of threads interposed between 120 the fixed guide and the adjustable guide, means for elevating the adjustable guide, said means including a plurality of flexible 124

cables each attached at one end to a fixed support, elevated pulleys engaged with said cables and supporting the same in bights or loops adapted to support the adjustable guide and rotary pulleys to which the opposite ends of the cables are attached, said pulleys being adapted to wind up portions of the cables, brake drums secured to said pul-

leys and brake shoes engaged with said drums.

In testimony whereof I have affixed my signature, in presence of two witnesses.

ALFRED K. MILLER.
